Attorneys

UNITED STATES PATENT OFFICE.

JOHN M. BRYSON, OF DETROIT, MICHIGAN.

KEY HOLDER.

Application filed April 29, 1922. Serial No. 557,351.

To all whom it may concern:

Be it known that I, JOHN M. BRYSON, a citizen of the United States of America, residing at Detroit, in the county of Wayne and State of Michigan, have invented certain new and useful Improvements in Key Holders, of which the following is a specification, reference being had therein to the accompanying drawings.

10 This invention relates to devices for detachably retaining a key in its lock so that it can not be pushed out by means of an instrument inserted in the lock from the outer side of the door, and its object is to provide 15 a simple device which may be cheaply manufactured from wire and which is so constructed as to preclude its accidental displacement and to provide for its application to different forms of keys. A further object is to provide a construction wherein the side members or legs of the device are crossed or interlocked to prevent accidental displacement of the device from the door lock to which it is applied and to provide a narrow 25 end portion which may be inserted in a small opening of a key or may be expanded to engage a key opening of comparatively large area. It is also an object to provide certain other new and useful features in the construction, all as hereinafter more fully described.

With the above and other ends in view the invention consists in the matters herein-after set forth and more particularly pointed 35 out in the appended claims, reference being had to the accompanying drawing, in which Figure 1 is a perspective view of a device illustrative of the invention and showing the same as applied to a door lock; and

40 Fig. 2 is a similar view of the device showing the same adjusted and applied to a key having a comparatively small opening.

The device which is the subject of the present invention is adapted for use in connection with door locks and latches having a knob or handle 1 provided with a rotatable shank portion 2 for operating the latch bolt 3, and provided with a locking bolt 4 operable by means of a key 5 insertable in the 45 lock through a key hole 6 in a face plate 7 secured to the inner face of the door 8, such lock and latch being of any old and well known construction and forming no part of

the present invention but being shown merely for the purposes of illustration

55

The device illustrative of the invention comprises a single piece of wire which is bent intermediate its ends to form a spring loop or eye 10, the wire being crossed at 11 to close the eye and then bent to bring the adjacent portions of the wire into parallelism and then again bent and crossed as at 12 in alternate relation to the crossing 11, thus forming an elongated closed loop 13 adapted to receive the shank 2 of the door 65 knob, said loop being of a width to loosely fit the shank and of a length to permit extended sliding movement of said loop upon the shank, longitudinally of the loop. Adjacent the crossing point 12, the wires are again bent and extended in substantial parallelism to provide an extended key engaging 70 end portion 14, the extreme end portions 15 of said wire being bent laterally toward each other to close the end of the key engaging loop 14 when the end faces of the wires are brought into contact with each other and are held in that position by the spring or yielding action of said wires, said inwardly bent 75 end portions 15 together forming a rounded 80 end for the key engaging loop so that it may be readily inserted in an eye or opening in the handle portion of the key where such key opening is of extended area, the loop 14 being extended in width by the engaged position of the opposed ends of the wire so that the key can not be turned sufficiently to throw the locking bolt when said end portion or loop is in the key opening. Where 85

the opening in the key is comparatively small, too small to receive the extended loop 14, the bent ends 15 of the wire may be sprung out of alinement as shown in Fig. 2, and past each other, thus permitting the sides of the loop to approach each other, 90

narrowing the width of the loop sufficiently to permit of its being inserted in the key opening. When sprung out of alinement these end portions pass each other at the side of the wire opposite that at which the 100 wires cross at 12 or the upper end of the loop and therefore end portions of the wire are interlocked so that they can not spread apart to interfere with their ready removal or insertion in the eye of the key, and as 105 the wires cross each other at 12 in alternate

relation to their crossing at 11, a closed loop is formed to receive the shank 2 which loop can not be readily opened or spread to release the device from said shank, thus pre-
 5 cluding the possibility of accidental displacement or detachment by a small child. As the end loop 14 is of considerable width, after disengagement of this loop from the eye of the key, said loop may be passed over
 10 the key to engage the shank portion of the key and further guard against the displacement of the device and also prevent it from swinging upon its support upon the shank 2. A key retainer which is simple in construction and very cheap to manufacture, is provided, and the construction of which is such as to facilitate its manipulation in use.

Changes in form and arrangement are contemplated and I do not therefore limit 20 myself to the particular construction, except as specifically set forth in the appended claims.

Having thus fully described my invention what I claim is:

25 1. A device of the character described formed of a single wire bent to form an elongated spring loop adapted to receive the shank of a door handle, said wire being crossed to close the lower end of said loop and extended beyond said point of crossing to provide a second key engaging loop

with the ends of said wire in abutting relation and held in engagement by the spring action of the wire, to close the lower of said second loop.

35 2. A key retainer formed from a single wire bent intermediate its ends to form a spring eye and the wire crossed to close said eye and extended to provide an elongated door-handle-shank engaging loop with the wire again crossed in alternate relation to the first named crossing to close the lower end of the elongated loop, the wire below said second crossing being extended to form a second elongated and comparatively narrow key engaging loop with the end portions of the wire bent inwardly to provide opposing end faces adapted to be held in engagement with each other by the spring action of the wire and to provide a rounded and closed lower end for said key engaging loop, said inwardly bent end portions being adapted to be forced laterally out of alinement with each other to lie side by side and bring the sides of said key engaging loop toward each other to decrease the width of said loop.

40 45 50 55 In testimony whereof I affix my signature in presence of two witnesses.

JOHN M. BRYSON.
